UNITED STATES PATENT OFFICE.

FREDERICK D. WILSON, OF MOLINE, ILLINOIS, ASSIGNOR TO DEERE & COMPANY, OF MOLINE, ILLINOIS, A CORPORATION OF ILLINOIS.

LEVER.

1,391,152.

Specification of Letters Patent. Patented Sept. 20, 1921.

Application filed October 3, 1919. Serial No. 328,227.

To all whom it may concern:

Be it known that I, FREDERICK D. WILSON, a citizen of the United States, residing at Moline, in the county of Rock Island and 5 State of Illinois, have invented certain new and useful Improvements in Levers, of which the following is a specification, reference being had therein to the accompanying drawing.

10 My invention relates to levers commonly employed for adjustment purposes, and the object of my invention is to provide such a device with a novel and effective means of holding the lever at any point of adjustment.

15 Referring to the drawings in which similar numerals indicate identical parts—

Figure 1 is a side elevation of my improved device.

20 Fig. 2 is a front elevation in part section.

Fig. 3 is a front elevation in part section and showing the lever released for operation.

25 Fig. 4 is a detail in part section showing the lever in engagement with a tooth of the sector, and

Fig. 5 is a detail of part of the lever.

On a support 1 is rigidly secured a sector 2. A lever 3 is pivotally supported on a bolt 30 4 which passes through the support 1 and the base 5 of the sector 2; on the free end of the lever 3 is the usual grip 6. Slidably mounted on the lever 3 is a casting 7 having a part 8 which extends above and to the side 35 of the arc of the sector 2 opposite the lever 3. Preferably integral with the part 8, and extending downwardly therefrom, is a projection 9 having its inner face beveled to contact with a similar bevel 10 on the adjacent edge of the arc of the sector 2. On the 40 lever 3, above the casting 7, is rigidly secured a member 11 between the under side of which and the top of the casting 7 is a coiled spring 12 held secured in place by a stud 13 45 on the member 11 and a similar stud 14 on the part 8 of the casting 7.

On the side of the arc of the sector 2 opposite the bevel 10 is a series of radially disposed teeth 15 any one of which is adapted 50 to engage with a slot 16 in the lever 3. Extending from one side of the part 8 of the casting 7 is an eye 17 in which the lower hook end of a rod 18 is engaged; the rod 18 extends upward and is connected to a

rockable grip 19 pivotally mounted on the upper portion of the lever 3.

As shown in Figs. 1 and 2 the lever 3 is held in position by one of the teeth 15 of the sector 2 engaging with the slot 16 in the lever, and the pressure of the projection 9 60 against the bevel 10 of the arc caused by the expansive force of the coiled spring 12. When it is desired to swing the lever 3 to a different position the two grips 6 and 19 are brought together raising the casting 7, 65 and as the latter raises lateral pressure is exerted by the operator to spring the lever 3 outward from the arc of the sector 2 to free the slot 16 from the tooth 15 with which it has been engaged. When the lever 3 is 70 free to be rocked either forwardly or rearwardly the parts are in position, as shown in Fig. 3, the end of the projection 9 having the limit of its upward movement below the upper edge of the arc, acts as a 75 stop to prevent the lever 3 from too great a lateral movement.

When the desired position of adjustment has been reached it is obvious that when the operator releases his hold upon the lever 80 3 the latter will spring back into place, the slot 16 engaging with the tooth 15 opposite to which the lever 3 has been moved; simultaneously with the spring of the lever 3 back into position, the casting 7 will move 85 downwardly under pressure of the spring 12 until the parts are as shown in Figs. 1 and 2, the bevel of the projection 9 resting firmly against the bevel 10 of the arc and holding the lever 3 securely in place. 90

What I claim is—

1. In a lever mechanism, the combination of a sector, a lever pivotally mounted to rock lengthwise of the sector, means on one side of the arc coacting with means on the lever to hold the latter from rocking, said means separable by springing the lever laterally whereby the lever is free to be rocked, and means on the lever in contact with the other side of the arc to hold the lever from lateral movement, said means adapted to be raised to free the lever simultaneously with the lateral swing thereof. 100

2. In a lever mechanism, the combination of a sector, a lever pivotally mounted to rock lengthwise of the sector, teeth on the side of the arc adjacent the lever, said lever provided with a slot to engage with any 105

one of said teeth to hold the lever from rocking, and means on the lever in contact with the side of the arc opposite the lever to hold the latter from lateral movement, said means adapted to be raised to free the lever simultaneously with the lateral swing thereof.

3. In a lever mechanism, the combination of a sector, a lever pivotally mounted to rock lengthwise of the sector, teeth on the side of the arc adjacent the lever, said lever provided with a slot to engage with any one of said teeth to hold the lever from rocking, a bevel on the opposite side of the arc, and a casting slidably mounted on the lever and having a downwardly extending projection in contact with the bevel of the arc to hold the lever from lateral movement.

4. In a lever mechanism, the combination of a sector, a lever pivotally mounted to rock lengthwise of the sector, teeth on the side of the arc adjacent the lever, said lever provided with a slot to engage with any one

of the teeth to hold the lever from rocking, a bevel on the opposite side of the arc, a 25 casting slidably mounted on the lever and having a downwardly extending projection, a bevel on said projection in contact with the bevel on the arc to hold the lever from lateral movement.

5. In a lever mechanism, the combination of a sector, a lever pivotally mounted to rock lengthwise of the sector, teeth on the side of the arc adjacent the lever, said lever provided with a slot to engage with any one 35 of the teeth to hold the lever from rocking, a bevel on the opposite side of the arc, a casting slidably mounted on the lever and having a downwardly extending projection, a bevel on said projection in contact with the bevel on the arc, a member rigidly secured on the lever, and a coiled spring interposed between said member and the casting to hold the bevels in contact whereby the lever is held from lateral movement.

FREDERICK D. WILSON.
